Specification for Design.

Patented Dec. 23, 1919.

Application filed May 21, 1919. Serial No. 298,790. Term of patent 3½ years.

To all whom it may concern:

Be it known that I, EMIL FUCHS, a subject of the King of England, residing at New York city, in the county of New York and State of New York, have invented a new, original, and ornamental Design for a Plaque, of which the following is a specification, reference being had to the accompanying drawing, forming part thereof.

The figure is a face view of a bas-relief or plaque, showing my new design.

I claim:

The ornamental design for a plaque, as shown.

EMIL FUCHS.
